[57] CLAIM

The ornamental design for a plate or similar article, as shown and described.

DESCRIPTION

FIG. 1 is a top plan view of a plate or similar article showing my new design;

FIG. 2 is a bottom plan view thereof;

FIG. 3 is an end elevational view thereof;

FIG. 4 is a side elevational view thereof;

FIG. 5 is a cross-sectional view taken along line 5—5 of FIG. 1; and

FIG. 6 is a cross-sectional view taken along line 6—6 of FIG. 1.

The characteristic feature of my design resides in the palmette-like decoration incised into the upper surface of the rim in combination with the configuration of the plate or similar article as best shown in FIGS. 1-5, and 6 on the drawing.
